LENS GRINDING AND POLISHING MACHINE

Lowell L. Houchin, Columbus, Ohio

Application June 12, 1936, Serial No. 84,835

11 Claims. (Cl. 51—64)

My invention relates to a lens grinding and polishing machine. It has to do, more particularly, with a machine for grinding and polishing lenses which is provided with a lens holder and a lap holder movable relative to each other, means being provided for simultaneously moving one of the elements both transversely and longitudinally relative to the other and additional means being provided for imparting a third movement so as to constantly change the path of movement and the extent of movement of one element relative to the other.

There have been a number of machines of the general type indicated above devised in the past. These machines usually embody a lap holder and a lens holder movable relative to each other. In order that the entire surface of the lens will be abraded by the lap, means is provided for moving one of the elements, usually the lens, relative to the other both transversely and longitudinally at the same time. However, in order to break up the lines of abrading and to reduce the chances of having inaccuracies in the finished lens, a third motion is usually employed. The third motion is accomplished by having additional means for moving the elements relative to each other so as to change the paths of travel of the movable elements during successive strokes and cycles of movement.

Although these prior art machines of the general type indicated have gone into extensive use, they are possessed of certain undesirable features. One of the greatest disadvantages of these prior art machines resides in the fact that they are of a complicated structure and, therefore, are expensive to construct and maintain. They are usually provided with a number of parts which do not wear for any appreciable length of time. Another great disadvantage of such prior art machines resides in the fact that they are so constructed that the third motion provided for breaking up the lines of grinding does not break up the lines sufficiently or as often as would be desirable. These prior art machines have been possessed of other undesirable features.

One of the objects of my invention is to provide a lens grinding and polishing machine which is provided with a lens holder and a lap holder, means being provided for simultaneously moving such elements relative to each other in two directions at right angles to each other, and additional means being provided for imparting a third movement to such elements so as to constantly change the path of movement and the extent of movement of one element relative to the other in or-

der to break up the lines of grinding to a greater extent and more often than with prior art machines and thereby obtain a more accurate surface on the lens.

Another object of my invention is to provide a machine of the type indicated which is of a very simple structure and is therefore inexpensive to construct and maintain and which is provided with a minimum number of parts which are subject to wear.

Another object of my invention is to provide a machine of the type indicated provided with means for bringing about three movements of the lens and lens-grinding lap relative to each other, such means being of such a nature that the three movements are independent of each other and, consequently, such movements may be controlled in such a manner that maximum breaking up of the lines of grinding will be obtained.

In its preferred form, my invention contemplates the provision of a machine embodying a base or housing having a frame disposed therewithin for movement longitudinally thereof. This frame has a portion extending through the forward wall of the housing and this portion carries a table upon which a plurality of laps may be mounted. I provide means for reciprocating the frame longitudinally of the housing and this means is adjustable at will to vary the extent of the longitudinal movement of the lap table which is carried by this frame. A second frame is disposed within the housing and has a plurality of forwardly projecting arms which carry lens-holding members adjacent their forward ends. These lens-holding members are so arranged that the lenses will contact with the surface of the laps which are disposed adjacent the forward wall of the housing. The frame that carries the lens-holding members is so constructed and supported that it may be rocked transversely of the housing so that the lenses will be reciprocated transversely relative to the laps. I provide means which is adjustable at will to change the extent of this transverse movement. Thus, it will be understood that the transverse movement of the frame that carries the lens-holding members and the longitudinal movement of the frame that carries the laps, which occur simultaneously, produces both transverse and longitudinal movement of the lenses relative to the laps. I also provide additional means for obtaining a third movement of the lenses relative to the laps so as to break up the lines of grinding. This means preferably comprises mechanism for imparting an additional transverse movement to

10

55

the frame that carries the lens-holding members in order to constantly change the extent and the path of the transverse movement of the lenses relative to the laps. This machine is of such a type that the three movements are independent of each other and the speed of each movement may be selected so that maximum breaking up of the lines of grinding will be accomplished.

10 The preferred embodiment of my invention is illustrated in the accompanying drawings wherein similar characters of reference designate corresponding parts and wherein:

15 Figure 1 is a perspective view of a complete machine made in accordance with the principles of my invention.

20 Figure 2 is a view, mainly in section, showing the mechanism which normally maintains a lens in contact with a lap.

25 Figure 3 is a plan view of the machine with the top of the housing removed, showing the operating mechanism thereof.

30 Figure 4 is a view mainly in side elevation, the side of the housing being removed to show the operating mechanism.

35 Figure 5 is a perspective view showing the operating mechanism of the machine.

40 Figure 6 is an end view of a bearing for supporting the frame that carries the lap tables.

45 Figure 7 is a side view of the same bearing.

50 Figure 8 is a view, mainly in section, of a different bearing structure used in supporting the frame that carries the lap tables.

55 Figure 9 is a view partly in section and partly in perspective illustrating the lap tables and supporting structure.

60 Figure 10 is a perspective view of a lap which I preferably use on my machine.

65 Figure 11 is a section showing an eccentric for controlling longitudinal movement of the frame that carries the lap tables.

70 Figure 12 is a section of an eccentric that controls transverse movement of the frame that carries the lens-holding members.

75 Figure 13 is a front view of the lap tables and supporting structure illustrating how this structure may be vertically or longitudinally adjusted.

80 Figure 14 is a diagram illustrating the path of movement of a point on a lens relative to the lens-grinding lap with which it contacts.

85 Figure 15 is a similar view illustrating the path of movement of the point on the lens relative to the lens-grinding lap after the machine has been adjusted to obtain a greater transverse movement than that illustrated in Figure 14.

90 With reference to the drawings, and particularly to Figure 1, my machine is shown as comprising a housing 1 which is preferably of substantially box-like form and is preferably made of metal. This housing preferably has a hinged door 2 at its top which is provided so that the operating mechanism of the machine may be reached for adjustment and other purposes.

Lap-carrier

95 In the machine illustrated I provide means for carrying two laps although it will be apparent that the machine may be modified to carry a single lap or any number of laps. I will first 100 describe the structure which I provide for carrying the laps in such a manner that they may be reciprocated longitudinally of the housing.

105 This structure is illustrated best in Figure 5. As shown, it comprises two supporting blocks 3 which are integrally secured to a plate 3a, which

is secured to the bottom of the housing, and these blocks are disposed at the ends of the plate. These blocks are located adjacent the forward wall of the housing and adjacent the ends of the housing. At the rear ends of these blocks a longitudinally extending rod 4 is supported in spaced relation to the plate 3a. This rod will not move longitudinally. At the forward end of each of the blocks 3 is disposed a bearing housing 5. These bearing housings 5 contain bearings which support 110 a longitudinally extending shaft 6 which is supported in such a manner that it may be reciprocated longitudinally of itself.

115 The bearings for supporting the shaft 6 for longitudinal movement are illustrated in detail in Figures 6 and 7. Each of these bearing structures comprises a pair of vertically spaced rollers 7 which are rotatably supported within the housing 5. These rollers are grooved and are spaced apart sufficiently to permit the shaft 6 to pass 20 therebetween. Thus, these rollers serve to support the shaft 6 so that it may be moved longitudinally with a minimum of friction.

25 The shaft 6 carries a member 8 which is adapted to support the lap table. This member 8 has a sleeve 9 formed thereon through which the shaft 6 extends. The member 8 is supported on the shaft in such a manner that it will not move longitudinally thereof. This member 8 extends forwardly through an opening or slot 10 formed in 30 the forward wall of the housing as illustrated in Figure 4. The extreme forward edge of the member 8 has an upstanding support 11 formed thereon. This portion 11 is disposed outside of the housing and adjacent the forward wall thereof. It is provided with a pair of vertically extending open-ended slots 12.

35 The member 8 extends rearwardly to a point adjacent the rod 4. This member 8 at its extreme rear end carries a bearing structure 13 40 which is provided for supporting the rear end of member 8 on the rod 4 in such a manner that the member 8 may be moved longitudinally of the rod. The bearing structure 13 is illustrated best in Figure 8. It comprises a pair of grooved 45 rollers 14 which are rotatably mounted, one of the rollers being disposed in front of the rod 4 and the other behind. Beneath the rod 4 a third roller 15 is rotatably mounted. This roller 15 has a flat surface which engages a flat surface 16 50 formed on the lower side of the rod 4. Thus it will be apparent that this bearing structure will support the rear end of the member 8 on the rod 4 so that it may be moved longitudinally along the rod with a minimum of friction. The member 55 8 will be supported in such a manner that friction will be reduced to a minimum. The roller 15 will take the thrust caused by the weight on the extreme forward end of the member 8. The rollers 14 and the rollers 7 guide the movement 60 of this structure and are so arranged that the member 8 may be moved longitudinally without vibration and with a minimum amount of friction.

65 Thus, it will be apparent that the member 8 may be moved longitudinally of the housing. The means for moving this member longitudinally of the housing will be described in detail hereinafter.

The lap tables and supporting structure

70 The lap tables and supporting structure are illustrated best in Figure 1, 4, 9 and 13. This structure embodies a single support 17 which carries a pair of lap tables. This support 17 is provided with a pair of longitudinally extending slots 18. Bolts 19 are preferably used for mounting 75

this support 17 on the support 11 at the extreme forward end of the member 8. The bolts 19 will extend through the slots 18 in member 17 and through the slots 12 in the member 11. Thus, it will be apparent that the member 17 will be adjustably supported on the member 11. The member 17 may be moved vertically or laterally relative to the member 11 (Figure 13) when bolts 19 are loosened, so that the member 17 may be properly positioned to properly locate the lap tables, and may be held in adjusted position merely by tightening the bolts 19.

The lap L which I preferably use on the machine is illustrated in Figure 10. It comprises a body portion having a flat lower surface in which a notch 20 is formed. The member 17 supports a pair of lap tables 21 which project forwardly therefrom. The upper surface of each of these tables is substantially flat but has a depression 22 formed therein in such a manner that an upstanding lug 23 is produced. This depression is formed mainly for the purpose of allowing the lap to rest on the outer edges only of the table in order to insure firm contact which will prevent rocking of the lap. The lug 23 projects above the surface of the table upon which the lap L will rest and is indicated best in Figure 4. The lug 23 will project into the notch 20 in the lower surface of lap L. The notch is just slightly wider than the diameter of the lug 23 so that when the lug projects thereinto, the notch and lug will cooperate to prevent longitudinal movement of the lap on the table. However, because the notch is elongated, as indicated, transverse movement of the lap on the table will be permitted.

I provide means for clamping the lap in position in order to normally prevent movement of the lap on the table. This means comprises a lug 24 with a straight forward edge arranged so that the rear edge of the lap will contact therewith and a clamping member 25 adapted to contact with the forward edge of the lap so that it will be firmly gripped between the clamping member 25 and the lug 24. The clamping member 25 is pivoted at its lower end as at 26 between a pair of ears 27 formed on the lower and forward portion of the table 21. The upper end of the clamping member 25 has a rearwardly projecting finger 28 adapted to engage the forward edge of the lap L as indicated in Figures 4 and 9. A screw 29 passes through the clamping member 28 intermediate its ends and is threaded into a bushing 30 disposed in an opening in the lap table 21. The screw is free to rotate in the opening in the member 25 through which it extends. The outer end of the screw is enlarged to form a handle portion 31, the inner end of which engages the clamping member 25.

It will be apparent that in using this clamping device, the lap L is placed on the table with the notch 20 over the lug 23. Since the notch is of substantially the same width as the diameter of lug 23, longitudinal movement of the lap on the table will be precluded. The handle 31 of the screw may be turned until the finger 28 touches the forward edge of the lap L and forces the lap transversely of the table into firm contact with the lug 24. The lap will be tightly gripped between finger 28 and lug 24. The notch 20 and the cooperating lug 23 serve to initially properly position the lap longitudinally of the table 21 and the clamping means serves to position it properly transversely of the table.

I provide means for effectively lubricating each

of the screws 29 in order to prevent binding thereof. It will be apparent that the moisture from the abrasive, which is usually in the form of a paste, would tend to rust the screws 29. However, I provide means for effectively lubricating the screws and thus eliminating any possibility of their rusting and binding.

This lubricating means comprises a reservoir 32 mounted on the member 17 intermediate the two lap tables 21. This member 32 has a cap 33 on its upper end which may be opened to permit filling with a lubricant. The lower end of the reservoir 32 is open and communicates with a vertical passageway 33a which in turn communicates with a horizontally extending passageway 34. The passageway 34 extends from the bore in which one of the screws 29 is disposed to the bore where the other screw is disposed. Thus, the lubricant is fed to the rear end of each of the screws 29. It will be noted that the screws are downwardly and forwardly inclined. Consequently, the lubricant will flow downwardly and forwardly along the entire length of the screws. Thus, the screws will be lubricated throughout their lengths.

The depression 22 in the lap tables will tend to collect any moisture which might seep beneath the laps and, therefore, will prevent sticking of the laps on the lap tables because of rust. The bottom of the housing 1 extends forwardly as indicated in Figures 1, 3 and 4 to form a shelf 1a which will catch any abrasive that falls off the laps.

To prevent any abrasive from reaching the operating mechanism of the machine I provide a guard member 35 which is secured to the rear edge of the member 17 as at 36 (Figure 4). The rear edge of this guard projects into a slot 37 formed in the forward wall of the housing. The guard 35 will move longitudinally with the lap tables and the rear edge will reciprocate in the slot 37. This guard will prevent abrasive from reaching the opening 10 through which the member 8 projects. However, it will be noted that the edges of the opening 10 are inclined downwardly as indicated at 38 so that if any abrasive reaches this opening, there will be a tendency for it to drop forwardly rather than rearwardly through the opening.

Lens-carrier

In this machine, I provide means for carrying two lenses although it will be apparent that the machine may be modified to carry any number of lenses and a corresponding number of laps. I will now describe the means which I provide for carrying the lenses in order that they may be moved transversely substantially at right angles to the movement of the laps.

The structure which carries the lens-holding members comprises a frame indicated generally by the numeral 39 which is mounted for rocking movement transversely of the housing. This frame 39 has a pair of depending legs 40 which are spaced longitudinally so that each of the legs 40 lies adjacent one of the blocks 3. The lower end of each of the legs 40 is pivotally mounted on a shaft 41 as at 42, there being a roller bearing disposed at this point to prevent wear. The shaft 41 extends longitudinally parallel to the shaft 6. Each end of the shaft is provided with a crank arm 43 which has one end keyed to the end of shaft 41 and has a pin 44 keyed to the other end which projects into an anti-friction bearing, such as a ball bearing disposed in a bearing support 45

50

55

60

65

70

75

which is mounted on the block 3. Thus, it will be apparent that an eccentric structure is provided at each end of the shaft 41. I will designate each of these eccentric structures generally by the numeral 46. It will be apparent that when these eccentrics 46 are rotated, the lower ends of the legs 40 will be moved both forwardly and rearwardly and upwardly and downwardly. In other words, the legs 40 will move in vertical planes in 10 a rotary path.

The frame 39 has a longitudinally extending portion 47 which connects the upper ends of the leg 40 together. Connected to this portion 47 is a rearwardly extending Y-shaped portion 48. 15 The rear end of this Y-shaped portion 48 is curved downwardly as at 49 and this curved portion is bifurcated. The extreme end of this portion 49 is connected to the lower end of a link 50a by a ball bearing pivotal connection. The upper end 20 of the link 50a is connected to an eccentric structure illustrated generally by the reference character 50. This eccentric 50 is illustrated best in Figure 12. It comprises a disk-like member 51 which is integrally formed with a shaft 52 that 25 is mounted for rotation on supports 53a disposed adjacent the rear end of the housing. This member 52 is provided with a T-slot 53 into which the headed end of a bolt 54 projects. This bolt 54 passes through an anti-friction self-aligning 30 bearing structure 55 and is held in position by a nut 56 and a lock-nut 56a. The upper end of link 50a has a collar 57 which fits around the bearing 55. Thus, I provide means for pivotally connecting the rear end of member 48 to the eccentric 35 structure 50. When this eccentric structure is rotated the frame 39 will be rocked about the pivot points 42.

Thus, the eccentric 50 will produce a transverse rocking movement of the frame 39. The 40 coaxially arranged eccentrics 46 will produce a different and independent transverse rocking movement of the frame. The extent of the movement produced by the eccentric 50 may be varied by changing the position of the bolt 54 in the slot 45 53 in disk 51. This bolt may be moved into alignment with the shaft 52 so that the eccentric 50 will be ineffective or may be moved outwardly to obtain movement of any desired extent. It 50 may be held in adjusted position by tightening the nut 56 and lock nut 56a.

The frame 39 has a pair of arms 59 pivotally mounted thereon in such a manner that the arms may rock both longitudinally and transversely of the machine. These arms are adapted to carry 55 lens-holding members. In order to mount these arms on the frame 39, the horizontal portion 47 of this frame is provided adjacent each end with a pair of upstanding supports which carry bearing 60 housings 60. These bearing housings 60 have roller bearings disposed therein and receive stub shafts 61 (Figure 3) which project thereinto and which are integrally secured to a substantially 65 rectangular member 62. The member 62 has a second set of stub shafts which project into ball bearings disposed in housings 63 (Figure 4) formed on the lower ends of depending portions 64 formed on the rear end of the member 59. The axes of the bearings in the housings 60 are disposed at right angles to the axes of the bearings 70 in the housings 63. Thus, it will be apparent that each of the arms 59 will be free to rock about its axis and will also be free to swing in a vertical plane about the pivot points 61.

The lens-carrying arms 59 project forwardly 75 through slots 65 formed in the forward wall of the

housing. The portion of each arm 59 that extends out of the housing is provided with a member 66 for carrying a lens block. This member 66 may be of any suitable type but preferably embodies a member having a pair of depending pins 5 67 that project into sockets formed in the upper surface of a block 68 to which is cemented or otherwise secured a lens L'. The pins 67 will permit movement of the lens and the lap relative to each other in both directions but will prevent 10 rotation of the lens relative to the lap. Consequently, this will insure that the curvature of the lap will be imparted to the surface of the lens.

Means for maintaining the lap and lens in contact 15

The means for maintaining the lap and lens in contact with each other firmly but resiliently is indicated best in Figures 1, 2 and 5. As illustrated, the forward portion of each arm 59 is downwardly turned as at 69 and then has a forwardly extending portion 70. This portion 70 is at a level substantially corresponding with the level where the lens L' and the lap L contact with each other. This portion 70 has a cup in its upper surface which receives a point 71 formed 25 on the extreme lower end of a rod 72. This rod 72 extends upwardly and has its upper end slidably mounted in a sleeve or collar 73 on the outer end of a pivoted arm 74. A compression spring 75 surrounds the rod 72 and the upper end of this 30 spring abuts a washer 76 disposed within the collar 73. The lower end of this spring bears against an enlargement 77 formed on the rod 72 adjacent its lower end. Thus, it will be apparent that the spring 72 will function to force 35 the forward end of the arm 59, that carries the lens, downwardly so that the lens will be in firm but resilient contact with the lap.

The arm 74 is pivoted at its rear end as at 78 to an upstanding support 79 which has its lower 40 end rigidly mounted between a pair of upstanding lugs 80 formed on the top of the housing. When the lap and the lens are in contact with each other, the arm 74 will be in substantially the position illustrated in Figure 4. I provide 45 latch mechanism for maintaining the arm 74 in operative position but which may be quickly operated in order to release the arm 74 to permit upward swinging thereof and, consequently, to permit upward swinging of the arm 59. I provide 50 a strap 81 which is adjustably connected to the forward end of the arm 74 as at 82 and is pivotally connected to the forward end of the arm 59 as at 83. This strap is provided so that when the arm 74 is swung upwardly the forward end of the arm 55 59 will also be lifted so that the lens block may be removed.

The latch for controlling the movement of arm 74 is illustrated best in Figure 2. As shown, this arm 74 is of hollow construction. It is pivoted to the member 79 as at 87 as previously indicated. The upper end of the member 79 has an arcuate shaped ratchet portion 84 formed on the forward edge thereof. It also has a socket 85 formed in its extreme upper end in which is disposed a compression spring 86. The upper end 60 of this compression spring bears against the arm 74 as at 87, lugs being provided for preventing displacement of the end of the spring. It will be 65 apparent that this spring 86 will normally tend 70 to swing the arm 74 upwardly about the pivot point 78.

A latch 88 is provided for cooperation with the ratchet 84 and is carried by the arm 74. The rear end of this latch 88 passes between guide 75

pins 89 disposed on the arm 74. The forward end of this latch 88 is pivoted to a trigger 90 as at 91, the trigger being pivoted to the arm 74 as at 92. A compression spring 94 has its upper 5 end disposed in a socket 95 formed in the arm 74 and its lower end in a socket formed in the upper surface of the trigger 90. The compression spring 94 normally tends to pivot the trigger 90 rearwardly about the pivot point 91 and 10 force the latch 88 rearwardly into cooperative relation with the ratchet 84. However, it will be apparent that if the trigger 90 is pulled forwardly, the latch 88 will be withdrawn from the ratchet and upward swinging movement of the arm 74 will be permitted, this upward movement 15 being produced by the spring 86 which will cause the arm 74 to pivot about the point 78.

It will be apparent that this latch mechanism is disposed substantially entirely within the arm 20 74. This latch mechanism will be automatically operative to hold the arm 74 in any position when it is swung downwardly. The spring 94 will tend to always maintain the latch 88 in contact with the ratchet. The compressive force 25 exerted by the compression spring 75 will depend upon the extent to which the arm 74 is swung downwardly. This force may be varied merely by pressing downwardly on the outer end of the arm 74 to cause it to swing further downwardly, the latch mechanism automatically locking it in position. To facilitate operation of the latch mechanism by means of the trigger 90 a hand grip 96 is provided on the forward end of the arm 74 in order that the trigger and the 30 portion 96 may be gripped simultaneously.

When the machine is not in use, as indicated in Figure 1, the latch mechanism will be released in order to permit automatic upward swinging of the arm 74 and, consequently, upward swinging 40 of the arm 59 so that the lens may be removed. When the machine is to be used again the lens is positioned on the lap and the arm 74 is swung downwardly which will cause the arm 59 to be moved downwardly, the spring 75 exerting sufficient force against the forward end 45 of the arm 59 to hold the lap and the lens firmly but resiliently in contact. As previously stated, the force exerted by the spring 75 will depend upon the extent to which the forward end 50 of the arm 74 is swung downwardly.

The fact that the point of application of the downward force by means of the rod 72 and spring 75 is substantially at the level of the point of contact of the lens and the lap makes it possible to grind strong plus lenses on the machine. A downward pull will be exerted on the lens rather than a downward thrust and this will make it possible to grind stronger plus lenses without danger of error.

In order to prevent any abrasive which might pass through the openings 65 from reaching the operating mechanism of the machine I provide a downwardly inclined guard member 97 which has its upper edge secured to the forward wall 65 of the housing and has its lower edge 98 upwardly turned. A similar guard 99 is secured to the frame 39 and extends in overlapping relationship to the guard 97. This guard 99 is downwardly and forwardly curved. It is of such 70 width that it will always overlap the guard 97 regardless of the position of the frame 39.

Longitudinal movement

As previously stated, the structure which carries the arms 59, that carry the lenses, is free to move longitudinally of the machine and such movement will cause longitudinal movement of the laps relative to the lenses. The means for accomplishing this longitudinal movement is indicated best in Figures 3, 5 and 11.

move longitudinally of the machine and such movement will cause longitudinal movement of the laps relative to the lenses. The means for accomplishing this longitudinal movement is indicated best in Figures 3, 5 and 11.

This means comprises a longitudinally extending pitman 100 which is pivotally connected as at 101 to an upstanding member 102 disposed substantially midway between the forward and rear ends of the member 8. A ball bearing is 10 preferably disposed at this pivot point. The other end of the pitman 100 is pivotally connected to a shaft 103, which is supported in a self-aligning ball bearing on the upper end of a support 104, by means of an eccentric indicated generally by the numeral 105.

The eccentric 105 is illustrated best in Figure 11. This eccentric comprises a disk 106 disposed eccentrically on the forward end of the shaft 103 and keyed thereon. A disklike member 107 is mounted on the member 106 and is free to rotate thereon being provided with a peripheral flange 108 that surrounds the member 106. This member 107 has a pivot pin 109 eccentrically disposed thereon which carries a 25 self-aligning ball bearing structure 111. Nuts 110 are threaded on the outer end of pin 109 to hold the bearing thereon. The end of the pitman has a collar 112 which surrounds this ball bearing structure. The disk 106 has a groove 30 113 in its periphery. Three members 114 project through the flange 108 of member 107 into the groove 113 and member 106. One of these members is an adjustable setscrew.

The shaft 103 and the pin 109 are usually out 35 of alignment with each other. Consequently, when the shaft 103 is rotated, the member 8 will be moved longitudinally of the machine by means of the eccentric structure 105 and the pitman 100. The extent of the longitudinal movement 40 may be varied by adjusting members 106 and 107 relative to each other. To do this the setscrew 114 is loosened and then the member 107 is rotated relative to the member 106. This will vary the position of the shaft 103 and the pin 45 109 relative to each other. Consequently, this will vary the extent of the lengthwise movement of the pitman 100. The shaft 103 and the pin 109 are so arranged that they may be brought 50 into alignment if desired, so that there will be no lengthwise movement of the pitman 100 and, consequently, no longitudinal movement of the member 8.

Transverse movement

As previously stated, the frame which carries the arms 59, that carry the lenses, is free to rock transversely of the machine and such rocking movement will cause transverse movement of the lenses relative to the laps. The means for accomplishing this transverse movement is illustrated best in Figures 5 and 12. As previously stated, this mechanism comprises the eccentric 60 illustrated generally by the reference character 50 and the link 50a which pivotally connect the 65 portion 49 of member 48 to the shaft 52.

When the shaft 52 is rotated, the eccentric 50 will rock the frame 39 about the pivot points 42. Consequently, due to this transverse rocking movement of the frame, the lenses will be caused 70 to move transversely relative to the laps. The extent of the transverse movement will depend upon the position of the pivot bolt 54 relative to the center of the disk 51 and this may be varied whenever desired.

Third movement

The means for accomplishing the third movement of the lap and lens relative to each other in order to break up the lines of grinding has been previously described. This means comprises the eccentric 46 which causes the frame 39 to move in a rotary path transversely of the machine. The longitudinal movement, the transverse movement, and the third movement, which also might be said to be a transverse movement, all occur simultaneously, as will be brought out more in detail hereinafter. All of these movements are independent of each other and the speed of each movement may be controlled independently of the speed of the others.

The third movement which breaks up the line of grinding and which is accomplished by means of the eccentric 46 will constantly vary the extent of the transverse movement produced by the eccentric 50. This is due to the fact that as the eccentric 50 causes the frame 39 to rock about the pivot point 42, the eccentrics 46 also rotate and cause the entire frame to move bodily forwardly and rearwardly. Thus, the extent of transverse movement produced by the eccentric 50 is constantly varied.

The eccentrics 46 are rotated by means of a pulley 115 which is keyed to one of the stub shafts 44 that is secured to a crank arm 43, the stub shaft extending through the bearing in the support 45. When the pulley 115 is rotated, the eccentrics 46 are rotated, both of them being rotated simultaneously because they are connected together by the shaft 41.

The driving means

The driving means of the various parts of the machine is illustrated best in Figures 3, 4 and 5. For driving these various parts of the machine I 40 provide electric motor 116. This motor 116 is supported within the housing adjacent the rear wall thereof. This motor may be controlled by means of a switch operated by a lever 117 (Figure 3) which extends through a slot 118 formed 45 in one of the side walls of the housing. Motor 116 is provided with a drive shaft 119. This shaft has a pulley 120 keyed thereon which drives the pulley 115, which controls rotation of eccentrics 46, by means of a belt 121. The pulley 50 120 and the pulley 115 are of substantially the same size so that the two eccentrics 46 will be driven at substantially the same speed as the drive shaft of the motor.

The drive shaft 119 has a second pulley 122 55 keyed thereon which is smaller than the pulley 120. This pulley 122 drives a larger pulley 123 by means of a belt 124. The pulley 123 is keyed on the end of shaft 52 which drives the eccentric 50 provided for obtaining the transverse movement of the frame 39. It will be apparent that the eccentrics 46 will be driven faster than the eccentric 50. Consequently, the transverse movement accomplished by means of eccentric 50 will be slower than the third motion accomplished 60 with the eccentrics 46. This results in the path of movement of the lens transversely of the lap, produced by eccentric 50, being changed several times, by means of eccentrics 46, during a single movement of the lens transversely of the lap from one edge thereof to the other. This insures that the lines of grinding will be broken up often and to a sufficient extent. The drive shaft of the motor projects through the side wall of the housing and on its outer end has a hand wheel 125 70 keyed thereto. This hand wheel 125 is provided

so that the drive shaft 119 may be rotated manually when the motor 116 is not running. This may be desirable to properly adjust the machine before operation thereof is started.

The drive shaft 119 of the motor also projects 5 from the opposite side thereof. It drives a gear reduction unit 126. This gear reduction unit 126 is connected to the shaft 103 that drives the eccentric 105 which produces the longitudinal movement of the structure that carries the lap 10 table. The gear reduction unit is provided so that the shaft 103 will be driven at a slower rate than the drive shaft. Thus, the longitudinal movement will also be at a slower rate than the third movement which is produced by means of 15 the eccentrics 46.

The operation

In operation of the machine, the laps L are first mounted on the lap tables in the manner 20 described. The lens blocks carrying the lenses are disposed in cooperative relation with the lap and the arms 59 are then lowered into operative position where the spring 75 will exert a downward force, causing the lenses to firmly contact 25 with the laps. The arms 59 may be moved into operative position merely by swinging the arms 74 downwardly, the latch mechanism carried by the arms 74 serving to automatically lock these arms in operative position in order that the spring 30 75 will force the lenses in firm contact with the lap. The motor 116 may then be started by means of the switch lever 117. This will cause the driving mechanism to function.

The eccentric 105 will be driven and will cause 35 reciprocation of the pitman 100. This will in turn cause longitudinal movement of the member 3 which carries the laps. Consequently, the laps will be reciprocated longitudinally relative to the lenses. The laps will move back and forth in a 40 horizontal plane.

At the same time the eccentric 105 is driven, the eccentric 50 is also driven. This causes 45 rocking of the frame 39 about the pivot points 42 and thereby produces transverse movement of the lenses relative to the laps. During this transverse rocking of the frame 39, the arms 59 which carry the lenses will pivot about the pivot points 61. Because of the longitudinal movement of the laps, the arms 59 will simultaneously pivot about 50 the axes of the bearings in the housings 63. In other words, the arms 59 will rock in a vertical plane and will also rock about their own axes.

Thus, it will be apparent that the lenses and the laps are moved relative to each other simultaneously in two directions substantially at right angles to each other. However, simultaneously with such movements in both directions, a third movement is produced by means of the eccentrics 46 which are driven comparatively fast. These 60 eccentrics produce a back and forth and up and down, in other words a rotary, movement of the frame 39. This causes a constant change in the path of movement of the lens and lap relative to each other since it varies the extent of the transverse movement produced by means of the eccentric 50. Since the eccentrics 46 are rotated at a greater rate of speed than the eccentric 50, the path of movement of the lenses transversely of the laps will be changed several times during 70 a single movement of the lenses transversely of the laps from one edge thereof to the other. This will insure that the lines of grinding will be broken up sufficiently to overcome any chance of error.

As previously described, the extent of the longitudinal movement may be varied at will by adjusting the eccentric 185. The extent of the transverse movement may be adjusted at will 5 by adjusting the eccentric 53. In Figure 14, I illustrate the path of movement of a point on the lens relative to the lap, produced when the lens is mounted on my machine and the machine is operated. Figure 15 is a similar view illustrating the path of movement when the pivot bolt 54 of the eccentric 53 is adjusted farther away from the center in order to obtain a greater transverse movement.

One of the important features of my invention lies in the fact that the three motions described are independent of each other. Thus, the speed of each movement may be different from the speed of the others. Because of this, it is possible to select speeds in such a manner 20 that the path of movement of the lens and the cooperating lap relative to each other is changed several times during a single stroke.

The fact that the relative longitudinal movement between the laps and the lenses is accomplished by moving the lap tables longitudinally rather than moving the lens-carrying members longitudinally is advantageous. The laps will be moved in a horizontal plane and will not be moved arcuately. This results in smoother operation and less friction than when the longitudinal movement is accomplished by moving the lens-holding members longitudinally and because of this, it is possible to grind stronger plus lenses without the usual difficulties.

It will be apparent from the above description that I have provided a machine having many desirable features. The machine is very simple yet very effective for the purposes for which it is intended. Any of the pivot points or bearing 40 points which might be subject to wear are provided with ball bearings. The machine is so constructed that the third movement provided therein is of such a nature that the lines of grinding are broken up to a greater extent and more often than with prior art machines.

Many other advantages will be apparent from the description and drawings and the following claims.

Having thus described my invention, what I 50 claim is:

1. A lens grinding and polishing machine comprising a lap holder and a lens holder movable relative to each other, means for moving the lap holder in a straight line only in one direction relative to the lens holder, means for moving the lens holder in a straight line only relative to the lap holder in a different direction and at an angle to the line of movement of the lap holder, both of said means operating simultaneously, and means for automatically varying the movement in one direction produced by one of said preceding means.

2. A lens grinding and polishing machine comprising a lap holder and a lens holder movable relative to each other, means for reciprocating the lap holder in a straight line only relative to the lens holder in one direction, means for reciprocating the lens holder in a straight line only relative to the lap holder at an angle to the first-mentioned reciprocation, both of said means operating simultaneously, and additional means for automatically varying the extent of reciprocation produced by one of said preceding means, said last-named means being of such a nature 70 that the path of movement of the lens holder and

the lap holder relative to each other is changed several times during a single stroke.

3. A lens grinding and polishing machine comprising a lap holder and a lens holder movable relative to each other, means for moving the lap holder in a straight line only relative to the lens holder in one direction, said means including an eccentric, means for moving the lens holder in a straight line only relative to the lap holder in a different direction at an angle to the line of movement of the lap holder, said means including an eccentric, and means for automatically varying the movement in one direction produced by one of the said preceding means, said last-named means including an eccentric. 15

4. A lens grinding and polishing machine comprising a lap holder and a lens holder movable relative to each other, means for moving the lap holder in a straight line only relative to the lens holder in one direction, said means including an eccentric, means for moving the lens holder in a straight line only relative to the lap holder in a different direction at an angle to the line of movement of the lap holder, said means including an eccentric, means for automatically varying the movement in one direction produced by one of the said preceding means, said last-named means including an eccentric, and means for driving all of said eccentrics in such a manner 20 that the last-named eccentric is driven at a higher rate of speed than the second-named eccentric. 25

5. A lens grinding and polishing machine comprising a lap holder and a lens holder movable relative to each other, means for moving the lap holder in a straight line only relative to the lens holder in one direction, said means including an eccentric, means for moving the lens holder in a straight line only relative to the lap holder in a different direction at an angle to the line of movement of the lap holder, said means including an eccentric, means for automatically varying the extent of movement produced by the means for moving the lens holder, said last-named means including an eccentric, and means for driving said eccentrics at different rates of speed. 35

6. A lens grinding and polishing machine comprising a frame which carries a lap holder, said frame being supported in such a manner that it may be moved longitudinally of the machine in a straight line only, means for moving said frame longitudinally of the machine, a second frame which carries a lens holder, said second frame being supported on the machine in such a manner that it may be rocked transversely thereof in a straight line only at an angle other than a straight angle relative to the line of movement of the first frame, means for rocking the second frame transversely of the machine, means for varying said transverse rocking movement, said means comprising an eccentric which carries said second frame and moves it bodily along the same line of movement produced by said second-named means, said second frame rocking about said eccentric during its transverse movement. 50 55

7. A lens grinding and polishing machine comprising a frame which carries a lap holder, said frame being supported in such a manner that it may be moved longitudinally of the machine in a straight line only, means for moving said frame longitudinally of the machine, said last-named means being manually adjustable to vary the extent of the longitudinal movement, a second frame which carries a lens holder, said sec- 70 75

- ond frame being supported on the machine in such a manner that it may be rocked transversely thereof in a straight line only at an angle other than a straight angle relative to the line of movement of the first frame, means for rocking the second frame transversely of the machine, said means being manually adjustable to vary the extent of the transverse movement, and means for bodily moving the second frame transversely and automatically along the same line of movement produced by said second-named means during the transverse movement produced by said second-named means, said means comprising an eccentric which supports said frame and about which the frame rocks during its transverse movement.
8. A lens grinding and polishing machine comprising a frame which carries a lap holder, said frame being supported in such a manner that it may be moved longitudinally of the machine in a straight line only, means for moving said frame longitudinally of the machine, said means comprising a rotatable eccentric operatively connected to the frame, a second frame which carries a lens holder, said second frame being supported on the machine in such a manner that it may be rocked transversely thereof in a straight line only at an angle other than a straight angle relative to the line of movement of the first frame, means for rocking the second frame transversely of the machine, said means comprising an eccentric operatively connected to the second frame, and means for bodily moving the second frame transversely and automatically along the line of movement produced by said second-named means during the transverse movement produced by said second-named means, said means comprising a plurality of co-axially arranged eccentrics which carry said second frame and about which the frame rocks during its transverse movement.
9. In a lens grinding and polishing machine a lap support, a lens support, one of said supports being pivotally mounted so that it may be swung into and out of operative position relative to the other, means for holding said support in operative relation to the other, said means comprising a spring-operated plunger rod which contacts with said support, said plunger rod being mounted on a support which is pivoted for swinging movement in a vertical plane, said plunger rod

and said last support being operatively connected in such a manner that as the support is swung downwardly the force exerted by the plunger rod increases, and an automatically operative latch mechanism for locking the support in any position to which it is swung to increase the effect of the plunger rod.

10. In a lens grinding and polishing machine, a lap support, a lens support, one of said supports being pivotally mounted so that it may be swung into and out of operative position relative to the other, means for holding said support in operative relation to the other, said means comprising a spring-operated plunger rod which contacts with said support, said plunger rod being mounted on a support which is pivoted for swinging movement in a vertical plane, resilient means for normally swinging said support upwardly, said plunger rod and said last support being operatively connected in such a manner that as the support is swung downwardly the force of the plunger rod increases, automatically operative ratchet and latch mechanism for locking the support in any position to which it is swung to increase the effect of the plunger rod, and manually operative means for releasing the latch and ratchet mechanism to permit said support to be swung upwardly automatically by said resilient means.

11. In a lens grinding and polishing machine, a lap support, a lens support, one of said supports being pivotally mounted so that it may be swung into and out of operative position relative to the other, means for holding said support in operative relation to the other, said means comprising a spring-operated plunger rod which contacts with said support, said plunger rod being mounted on a support which is pivoted on the machine for swinging movement in a vertical plane, resilient means for normally swinging said support upwardly, said plunger rod and said last support being operatively connected in such a manner that as the support is swung downwardly the force exerted by the plunger rod increases, a ratchet rigidly carried by the machine, a latch carried by the support, said latch being spring-pressed so that it always engages said ratchet, and a trigger for releasing said latch from said ratchet.

LOWELL L. HOUCHIN.
